UNITED STATES PATENT OFFICE.

JOHN CURRIN, OF NEW YORK, N. Y.

EYEGLASS-CASE.

1,080,267.

Specification of Letters Patent.

Patented Dec. 2, 1913.

Application filed March 27, 1912. Serial No. 686,669.

To all whom it may concern:

Be it known that I, JOHN CURRIN, of New York, in the county of New York, and in the State of New York, have invented a 5 certain new and useful Improvement in Eyeglass-Cases, and do hereby declare that the following is a full, clear, and exact description thereof.

My invention refers to an improvement in 10 eye-glass cases, and more particularly to the interior construction of such a case, the purpose of which is to prevent eye-glasses carried within the case, from being broken when the case is dropped upon the floor or 15 other hard object.

It has been frequently found in the past 20 that eye-glasses are oftentimes sufficiently fragile to be broken even within the eye-glass case of the usual type when the case and glasses are dropped a short distance upon some hard object, and it is my purpose to avoid this disadvantage of eye-glass cases now in use.

The eye-glass case which is constructed in 25 accordance with my invention, comprises in general, a case which is provided upon its interior with a spring-means or padding, and means for maintaining the lenses of the eye-glasses in such a position that they will 30 not have any free play relative to the eye-glass case and so that any shocks which are received by the eye-glass case will not be transmitted to the lenses.

I have shown certain embodiments of my 35 invention in the accompanying drawings, in which:

Figure 1 represents a plan view of an eye-glass case shown in the open position; Fig. 2, is a cross section of the lid of the case 40 shown in Fig. 1 taken on the line 2—2; Fig. 3, is a plan view of another form of eye-glass case made in accordance with my invention; and Fig. 4 is a cross section of the lid shown in Fig. 3 taken on line 4—4 of 45 said figure.

In Figs. 1 and 2, 1 represents the body of an eye-glass case having a spring-operated lid 2 of the usual type. The lid 2 carries a pair of cloth-covered springs 3 which are 50 situated in such a position that when the case is closed the springs 4 will be directly

opposite a similar pair of cloth covered springs 4 located on the body of the case. Each of these springs 3 and 4 is a conically shaped spiral spring having at its apex a 55 body 4' to make a round surface for the cloth cover to fit over.

When a pair of eye-glasses 5 is inserted in the case and the case closed, the lenses fall directly between the springs 3 and 4, 60 so that as a consequence, when the case is closed, the lenses of the eye-glasses 5 are yieldingly supported in the center of the eye-glass case.

In Figs. 3 and 4 I have shown another 65 modification of my invention in which 6 represents a flat spring having a central narrow portion 7 attached to the center of the body 1 by means of a screw or rivet 8 and having also a pair of wings 9 which are 70 rounded and bent upwardly as shown in Fig. 4 beneath a cloth cover similar to that shown in Fig. 2 to present a rounded surface to the lenses of the eye-glass, as in the modification already described. Each of the 75 wings 9 is provided with a circular opening 10 at its center so as not to bring a pointed surface opposite the lenses of the eye-glass. Lid 2 is provided with a similar flat spring 11 having wings 12 similar in every way to 80 the wings 9 already described. This modification of my invention operates substantially in the same manner as the modification shown in Figs. 1 and 2.

When an eye-glass case constructed in accordance with my invention and containing a pair of eye-glasses happens to fall upon a hard object, the lenses are not brought into contact with any of the hard portions of the eye-glass case and the shocks which may be 90 received by the case itself are not transmitted to the lenses. In this manner, the eye-glasses may be effectually preserved against breakage when the eye-glass case is accidentally dropped.

While I have described certain embodiments of my invention above in detail, I wish it to be understood that many changes may be made therein without departing from the spirit of my invention.

I claim:

1. In a device of the character described,

- the combination of a case and means for supporting eye-glasses therein, comprising a covered spring having a rounded body located between the spring and its cover.
- 5 2. In a device of the character described, the combination of a case and means for supporting eye-glasses therein, comprising opposed covered springs, each of said springs

having a rounded body located between the spring and its cover. 10

In testimony that I claim the foregoing I have hereunto set my hand.

JOHN CURRIN.

Witnesses:

JOHN H. HARTUNG,
CHAS. E. WEBER.
